UNITED STATES PATENT OFFICE.

GEORGE F. DOWNS, OF BUFFALO, NEW YORK.

MOLD FOR CASTING METAL INGOTS.

1,174,131.

Specification of Letters Patent. Patented Mar. 7, 1916.

Application filed December 11, 1915. Serial No. 66,241.

To all whom it may concern:

Be it known that I, GEORGE F. DOWNS, a citizen of the United States, and a resident of Buffalo, in the county of Erie and State of New York, have invented certain new and useful Improvements in Molds for Casting Metal Ingots; and I do hereby declare that the following is a full, clear, and exact description thereof, reference being had to the accompanying drawings, and to the letters of reference marked thereon, which form a part of this specification.

This invention relates to improvements in molds for casting metal ingots and consists of the matters hereinafter described and more particularly pointed out in the appended claims.

The object of the invention is to produce a commercially practicable mold for the purpose described of such construction, that the cooling and solidification of the hot metal forming the ingot is retarded toward the top of the mold, so as to prevent the formation of blow holes, pipes, fissures and the like in the body of the ingot and to reduce to a minimum the usual cavity or pocket at the top of the ingot.

Another object is to provide such a mold with means by which it may be stripped from the finished ingot by any of the standard stripping machines in use at the present time.

In the drawings:—Figure 1 is a view in side elevation of a mold for use in casting metal ingots made in accordance with my invention. Fig. 2 is a vertical sectional view, the plane of the section being indicated by the line 2—2 of Fig. 1. Fig. 3 is a horizontal sectional view, the plane of the section being indicated by the line 3—3 of Fig. 2.

Referring now in detail to that embodiment of my invention illustrated in the accompanying drawings:—5 indicates the body of the mold, which incloses the chamber 6 in which the ingot is cast. The body of the mold, made usually of cast iron, is as shown substantially rectangular in cross section and is made tapering toward the top, the chamber 6 tapering in a like manner. The bottom end of the chamber 6 in which the ingot is cast is closed by a stool 7 which forms the bottom wall and support for the mold.

8 indicates a metal sleeve which is adapted to be supported or hung from the top edge 55 of the mold, and which is of the same cross-

sectional form as the mold but of larger size so as to provide a jacket space 9 about the upper part of the mold. Said sleeve preferably incloses nearly one half of the length of the mold. The sleeve 8 has at the top an inwardly extending horizontal flange which rests upon the top of the mold. Said sleeve has an upright shoulder 9^a extending downwardly from the flange 11 and spaced from the mold a sufficient distance to allow for expansion, while at the same time preventing displacement of the sleeve. The flange 11 defines the pouring opening or mouth 12 for the mold chamber 6, and provides a closure or seal for the top of the jacket space 60 65 9. The sleeve 8 is preferably recessed as illustrated on its inner surface, to receive a lining 13 of fire brick or other suitable non-heat conducting material, although this is not essential.

14 indicates a closure or seal for the bottom end of the jacket space 9. This includes a ring 15 having a horizontal web 16 formed to closely engage the outside surface of the mold in a plane a short distance below the 70 bottom of the sleeve 8, and having an upright flange 17 surrounding and spaced from the sleeve 8 and extending vertically above the plane of its bottom end. The upright flange 17 of the ring and the adjacent wall of the mold define a trough into which the bottom end of the sleeve 8 depends and which provides support for a packing ring 18 of non-heat conducting material such as ordinary clay or loam which effectually seals 75 80 85 the bottom end of the jacket space 9.

In preparing the mold for use, the ring 15 is placed upon the mold body and the trough thus provided is filled with the clay or loam to form the packing ring or seal 18. 90 The sleeve 8 is then placed upon the mold body with its bottom edge engaging the loam packing. Pressure is then brought to bear upon the top end of the sleeve 8 to force its bottom end into the said packing 100 until the flange 11 at the top is brought down upon the top of the mold. A closed insulating air jacket is thus formed about the top of the mold.

When the molten metal is first poured 105 into my improved mold, it will be kept in a molten condition for a comparatively long period of time, since the bottom part of the mold body, being thickest, will absorb more of the heat from the molten metal and tend 110

to cause solidification first at the bottom. As the rising level of the molten metal approaches the plane of the sleeve, such heat as is taken up from the molten metal by the 5 mold body is transmitted or radiated to the air within the air space or jacket 9. The sleeve 8 with the associated ring and seal acts to conserve the insulating air in this chamber for a considerable period of 10 time, thus retarding the cooling and consequently the solidification of the metal forming the ingot in the top of the chamber 6. In this manner the molten metal forming the ingot is retained in a liquid state for a 15 considerable period of time. The process of cooling the molten metal being thus retarded, there is time for the hot metal to flow and to assume new relations as it cools and for the air and gases trapped in the 20 molten metal in the process of pouring to work upwardly and out of the liquid mass, thus preventing the formation of blow holes, and like imperfections as well as elevating the shrinkage cavity to the top of the ingot. 25 To provide lugs for stripping my improved mold by means of any standard stripping machine, I adopt the following construction: 20, 20 indicate removable hooks or lugs. Each hook or lug is in the 30 form of a vertically arranged bar or strap 21, 21. Said bar is pivoted at its bottom end to laterally projecting spaced ears 22 formed on opposite sides of the mold body, below that part of said body engaged by the 35 sealing ring 15. A removable axis pin 23 pivotally connects each bar to the associated ears. The top end of each bar is bent outwardly to provide a hook 25, and the bottom end of each bar is formed to provide 40 a heel 24 adapted to engage against the mold body and limit the outward swing of the lugs upon its pivot pin 23, as illustrated by the dotted lines in Fig. 2.

It is apparent that should the body of the 45 mold become cracked or otherwise unfit for use, the stripping lugs may be removed therefrom and placed upon new molds. The sleeve 8, after once being adjusted to or placed upon a mold remains thereon until 50 the mold wears out, when it may be removed as a whole, together with the seal ring and placed upon a new mold.

My improved mold on account of its simple construction is commercially practical 55 and usable and the insulating sleeve thereof presents a substantial top which can in no manner be damaged by the uncontrolled flow of molten metal from the ladle which sometimes occurs during the pouring operation. 60

I am aware that several molds have been designed to accomplish the aim attained by my improved construction, but they are 65 too expensive to make them commercially usable as they have to be adjusted to and

removed from the mold body before and after the pouring of each ingot and require attention during the solidification of the ingot within the mold.

I claim as my invention:—

1. A mold for casting ingots, comprising in combination with the mold body, a sleeve surrounding the top part of the mold body and inclosing a jacket space about the same, said sleeve having an inturned flange at its 70 upper end resting upon the top end of the mold body, and means for sealing the bottom end of said sleeve against the adjacent part of the mold body to close the bottom end of said jacket space.

2. A mold for casting ingots, comprising in combination with the mold body, a sleeve surrounding the top part of the mold body and inclosing a jacket space about the same, said sleeve having an inturned flange at its 75 upper end resting upon the top end of the mold body and defining the pouring opening of the mold, and means for sealing the bottom end of said sleeve against the adjacent part of the mold body to close the bottom 80 end of said jacket space.

3. A mold for casting ingots comprising in combination with the mold body, a sleeve surrounding the top part of the mold body and inclosing a jacket space about the same, 95 said sleeve having an inturned flange at its upper end resting upon the top end of the mold body, and being provided with a depending shoulder below said flange embracing but spaced a short distance from the 100 top end of the mold to allow for expansion of the same, and means for sealing the bottom end of said sleeve against the adjacent part of the mold body to close the bottom end of said jacket space.

4. A mold for casting ingots, comprising in combination with the mold body, a sleeve surrounding the top part of the mold body and inclosing a jacket space about the same, said sleeve having an inturned flange at its 110 upper end resting upon the top end of the mold body, and means for sealing the bottom end of said sleeve against the adjacent part of the mold body to close the bottom end of said jacket space, said means consisting of a ring providing in conjunction with said body a trough into which the bottom end of said sleeve depends and a packing of clay or loam within which the bottom end of said sleeve is embedded.

5. A mold for casting ingots, comprising in combination with the mold body, a sleeve surrounding the top part of the mold body and inclosing a jacket space about the same, 125 said sleeve having an inturned flange at its upper end resting upon the top end of the mold body, a ring having a horizontal web engaged about the body of the mold and an upright flange spaced from and projecting above the bottom end of the sleeve, and a 130

seal of loam or clay supported by said ring in which seal the bottom end of said sleeve is embedded.

6. A mold for casting ingots, comprising 5 in combination with the mold body, a sleeve surrounding the top part of the mold body and supported from the upper end thereof, said sleeve inclosing a jacket space about said mold body, and detachable extension 10 stripping lugs attached to said mold body in a plane below the end of said sleeve.

7. A mold for casting ingots, comprising in combination with the mold body, a sleeve surrounding the top part of the mold body 15 and inclosing a jacket space about the same, said sleeve having an inturned flange at its upper end resting upon the top end of the mold body, means for sealing the bottom end of said sleeve against the adjacent part 20 of the mold body to close the bottom end of said jacket space, and detachable extension stripping lugs pivoted to the mold body in a plane below the end of said sleeve.

8. A mold for casting ingots, comprising 25 in combination with the mold body, a sleeve surrounding the top part of the mold body and inclosing a jacket space about the same, said sleeve having an inturned flange at its upper end resting upon the top end of the 30 mold body, means for sealing the bottom end of said sleeve against the adjacent part of the mold body to close the bottom end of said jacket space, spaced ears made rigid with the mold body in a plane below the

end of said sleeve, extension stripping lugs 35 extending from said ears to the top of said mold body, and removable pivot pins for attaching said stripping lugs to said ears.

9. A mold for casting ingots, comprising in combination with the mold body, a sleeve 40 surrounding the top part of the mold body, and inclosing a jacket space about the same, said sleeve having an inturned flange to close the top of said jacket space, and means for supporting a loam or clay seal in the 45 plane of the bottom end of the sleeve to close the bottom of said jacket space.

10. A mold for casting ingots, comprising in combination with the mold body, a sleeve surrounding the top part of the mold 50 body and inclosing a jacket space about the same, said sleeve having an inturned flange at its upper end resting upon the top end of the mold body, said sleeve having its inner surface recessed to provide a channel 55 surrounding said jacket space, a fire brick lining in said channel, and means for sealing the bottom end of said sleeve against the adjacent part of the mold body to close the bottom end of said jacket space. 60

In testimony that I claim the foregoing as my invention I affix my signature in the presence of two witnesses; this eighth day of December, A. D. 1915.

GEORGE F. DOWNS.
